(57) **CLAIM**

The ornamental design for a stock for a firearm, as shown
and described.

DESCRIPTION

FIG. 1 is a right, forward, upper perspective looking rearward view of a stock for a firearm showing my (our) new design;

FIG. 2 is a right, forward, lower perspective looking rearward view thereof;

FIG. 3 is a right, rear, upper perspective looking forward view thereof;

FIG. 4 is a right, rear, lower perspective looking forward view thereof;

FIG. 5 is a top view thereof;

FIG. 6 is a right elevation view thereof;

FIG. 7 is a bottom view thereof;

FIG. 8 is a left elevation view thereof;

FIG. 9 is a rear elevation view thereof; and,

FIG. 10 is a front elevation view thereof.

The broken lines in the drawings depict portions of the
article that form no part of the claimed design.
